UNITED STATES PATENT OFFICE.

RODNEY J. WOOD, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND.

SALES BOOK.

Application filed April 21, 1919. Serial No. 291,526.

This invention relates to improvements in a sales book which may be used as a day book in addition to its use as a sales book. One object of the invention is to retain in 5 the hands of the merchant a bound set of the numbered carbon copies of sales slips while at the same time issuing to the customer an original sales slip which is torn out of the sales book. There is also a corresponding sales slip to be retained by the merchant and filed in a cash register drawer or a credit file as is well known in the art.

Another object of the invention is to provide upon the inside of an outside cover 15 spaces to receive an itemized sales record, in which entries are to be made at the time of each transaction and thus provide the merchant with a classified statement of his business, showing the extent of the sales of 20 the various commodities handled by him.

Still another object of the invention is to provide a permanent compact file the respective parts of which may be numbered consecutively and may be dated to 25 indicate the portion containing that day's business, and thus providing a ready reference means for business transactions upon any selected date without reference to the various accounts posted from that date.

Another object of this invention is to 30 adapt the loose slips issued in connection with a charge transaction for use in a credit file of well known form to which reference is made later. When so used the loose copy 35 with proper entries thereon retained by the merchant is disposed of by placing the same in said credit file.

Still another object of this invention is to 40 provide means for making an exact copy of the original entry and thus retain all the characteristics of the slip handed to the customer upon the slip corresponding thereto and retained by the merchant in the slip form or in the bound form as distinguished above.

The character of a credit file to which 45 the slips from the sales book are adapted is completely set forth in Letters Patent of the United States of Rodney J. Wood, No. 50 1,313,150 issued Aug. 12, 1919. In connection with the use of the detachable slips from this sales book in the above mentioned credit file the same may be inserted in a slip printing cash register where they may

receive an indication of the character of the 55 transaction, indication of the clerk conducting the transaction, the amount thereof, the number of the same, and the date of said transaction. It is of course apparent that these detachable slips are not restricted in 60 any way to use with either a credit file or a cash register, for it is perfectly clear that they are useful adjuncts to a business where neither of said devices is in use.

The subject matter printed upon the slips 65 shown in this application relates to the business of a garage but there is of course no limitation to be presumed on this account as the sales book is applicable in its use 70 to many other kinds of business.

With the above and incidental objects in view, the invention consists in certain novel 75 features of construction and combinations of parts, the essential elements of which are set forth in the appended claims and a preferred form of embodiment of which is hereinafter specifically described with reference to the drawings which accompany and form part of the specification.

Of said drawings:

Fig. 1 represents the sales book with certain 80 of the removable slips in position and shows the record upon the bound sheet of the complete transaction.

Fig. 2 is an end view of two of the removable slips and the bound sheet and shows the distribution of the copying carbon.

Fig. 3 shows the sales book with a portion 85 of the retainer broken away and the body thereof turned back so as to clearly disclose 90 the arrangement of the lines and columns on the inside surface of the cover whereon is entered the distribution of sales.

Fig. 4 shows a plan view of the sales 95 book wherein the detachable slips with copying carbon thereon are removably connected along one of their longer edges.

Fig. 5 shows the sales slips arranged in blocks as distinguished from the layers of 100 the former figures, each block being separate from the adjacent block.

The sales book comprising the detachable 105 slips and non-detachable sheets has a cover 1 fastened by staples 2 for which may be substituted any equivalent binding. The inner surface 3 of the cover is suitably ruled for the entry thereon of the various items under the headings which form the basis

for the distribution of the business transactions. Firmly held in the cover 1 are one piece or integral sheets 4 each carrying upon its under surface copying carbon 5. Each sheet 4 is blank except for numerals designated 6 which are the same as those upon detachable slips used in connection with the transaction to be recorded upon an assigned portion of said sheet.

- 10 Adjacent to the sheet 4, that is above and beneath, are the customer's slip 7 and the merchant's slip 8 which are arranged in two or more groups depending on the size of the book, and are rendered together detachable 15 from the sales book and separable from each other by perforations 9. In Fig. 1 is found sheet 4 which is broken away showing the printed subject matter upon the slip 8 to be the same as that upon slip 7. By the use 20 of the carbon surfaces 5 and 11 the writing upon the customer's slip 7 is copied through to the underlying merchant's slip 8, and thus the original writing of the merchant or his employee is made upon the outer slip 7 and a carbon copy is made upon the sheet 4 and the slip 8 in a well known and often 25 practiced manner. As both slips and the sheet 4 bear the same numeral 6 each transaction is automatically numbered.
- 30 After the transaction has been completed by the entry of a single item or a number of items and the head of the slips has been filled out the said slips are removed from the sales book and slip 7 is handed to the 35 customer while slip 8 is retained by the merchant to be dealt with later as desired, such as for posting to the ledger if preferred rather than to post from the sheet 4 remaining in the cash book or day book. In the 40 case of the presence of a slip printing cash register the detached slips 7 and 8 are properly inserted therein and the amount of the transaction is set up on the keys of the cash register which upon proper manipulation 45 enters the amount thereof and the character of the transaction in said register and prints the same and additional information upon the slips. Should the transaction be a credit sale as distinguished from a cash sale, indication thereof is made upon the slips by the register. When the amount involved 50 in the transaction is to be charged to the account of the purchaser the clerk prior to making out the entries on slip 7 refers to the credit file above noted and enters opposite the heading on the top of the slip calling for the balance on the account the amount forwarded or the standing of the customer's account prior to the present 55 transaction. After entering all the items the clerk then totals the amount forwarded with the amounts of the items involved in the present sale which total will be the amount owing to date. When slip 7 is handed to the customer slip 8 is immediately

transferred to the credit file under the customer's name.

Having printed the proper data on the slips by means of the cash register and having placed the slip 8 in the credit file it is necessary for the clerk to enter upon the inner surface 3 of the cover 1 the various items of the transaction so as to obtain the desired distribution of sales. The use of the inner surface 3 is clearly shown in Fig. 3. 70

A modified form of the sales book comprising the invention embodied in this application is shown in Fig. 4 wherein the slips 7 and 8 are detachably connected to the sales book upon one of their longer edges and are connected to each other by a perforated line along the other longer edge and are bound in said book adjacent to each other instead of being separated by the bound sheet 4. The use of the modified form is substantially the same as that described above.

The arrangement of the sales slip and the sheet 4 is such that the inner surface 3 of the cover 1 for distributing the sales is laid out practically the same as in Fig. 1 except that the items for the distribution are disposed along a short edge thereof.

Another modified form of the invention is shown in Fig. 5 wherein the sheets 4 and the detachable slips 7 and 8 are bound in a block and numbered from top to bottom as distinguished from the foregoing forms of the invention wherein sheet 4 has been referred to as an integral sheet. It is perfectly obvious that in the preceding description of this invention the sheet 4 might vary well have been divided into respective sheets rather than remaining intact as an integral sheet. However, in the present modification in connection with the arrangement of the bound sheet with the slips in a block it has been found desirable to separate the sheet as noted and here we find sheet 4 interposed between the slips 7 and 8. This arrangement is not a fixed one as 7 and 8 might very well be adjacent each other with the proper distribution of copy carbon thereon so as to convey the record to each other and the sheet 4. In this form of the invention the inner surface 3 of the cover 1 is narrow and while not shown ruled may or may not be used for keeping a record of the distribution of business. Each block, it will be noted, has printed upon the formed edge 14 thereof the number of the included sheets and a space for the date of the last sheet so that ready reference may be made thereto when the used sheets 4 have been set away as a permanent file. 110

In order to retain the blocks of slips and sheets and a flap 15 of the cover in the position shown in the right hand portion of Fig. 5, a tang 13 is attached to the cover 1 and extends therefrom and over one edge 125 130

of the slip 7. The character of the tang 13 is such as to confine the sheets and slips and flap 15 as compactly as possible and serves to prevent them from bulging and forming a package inconvenient to file and handle.

The extensions or flaps 15 in the several modifications illustrated not only constitute covers for the books but also operate as supports for every portion of the slips and record sheets under which they are placed. When so used the flaps also serve as stop-cards to prevent impressions from being made upon any of the slips or sheets that are below them.

While the form of device herein shown and described is admirably adapted to fulfill the objects primarily stated, it is to be understood that it is not intended to confine the invention to the one form of embodiment herein disclosed, for it is susceptible of embodiment in various forms all coming within the scope of the claims which follow.

What I claim is:—

- 25 1. In a sales book, a plurality of groups of numbered sheets, a binder common to said groups, a separate cover for each of said groups, and means on the covers identifying the numbered slips enclosed thereby.
- 30 2. In a sales book, a plurality of separate groups of consecutively numbered sales slips, a plurality of non-detachable sheets common to all of said separate groups of sales slips, numbers on said sheets identifying the numbers employed in consecutively numbering the sales slips of each group, a binder common to said groups of

sales slips and sheets, and a cover for said groups of sales slips and sheets.

3. In a sales book, the combination with a cover, of a plurality of separate sales slips arranged in independent groups and removably secured in alignment to the cover, each sales slip of each group comprising an original leaf and a larger duplicate leaf, connected together along one edge and folded so that the original leaf overlies the duplicate leaf, and a single record sheet permanently secured to the cover and common to a sales slip of each of the independent groups of slips.

4. In a sales book, the combination with a single binder or support, of a plurality of separate groups of consecutively numbered sheets, which groups are arranged successively on the common binder, each group of sheets after the first bearing a series of numbers numerically following the series of numbers on the preceding group of sheets.

5. In a sales book, the combination with a single binder or support, of a plurality of separate groups of consecutively numbered sheets, which groups are arranged successively on the common binder, each group of sheets after the first bearing a series of numbers immediately following the series of numbers on the preceding group of sheets, a cover for each of the groups of sheets, and data on the cover to identify the numbers on the group of sheets enclosed by such cover.

In testimony whereof I affix my signature.

RODNEY J. WOOD.
